UNITED STATES PATENT OFFICE.

REINHOLD H. WAPPLER, OF NEW YORK, N. Y.

CYSTOSCOPE.

No. 879,224.

Specification of Letters Patent.

Patented Feb. 18, 1908.

Application filed August 28, 1906. Serial No. 382,372.

To all whom it may concern:

Be it known that I, REINHOLD H. WAPPLER, a citizen of the United States, and resident of the city of New York, in the county of New York and State of New York, have invented certain new and useful Improvements in Cystoscopes, of which the following is a specification.

This invention relates to a device which may be designated as a cystoscope and is intended to be used in examination of parts of the body by physicians and surgeons for treatment in diseases of various kinds on various parts of the body which are not easily accessible for such examination and treatment.

The device consists primarily of a main body portion or sheath of tubular form provided at one end with a rounded cap for closing the same and also with fenestral openings, opposite which is positioned a lamp for illumination. The circuit for this lamp is supplied by an insulated wire which is placed in a small tube and which is in turn placed in a slot in the wall of the sheath. The other side of the circuit may be formed by the sheath itself. This method of placing the wire lead in a slot leaves the tubular opening in the sheath free and clear and also provides a smooth and uniform exterior surface for the same.

The fenestral openings in the sheath on opposite sides of the lamp are of relatively large size and allow the light to pass in every direction from the lamp. This permits the examination of all of the surrounding parts of the body and, by the use of suitable reflectors, a view rearwardly may also be obtained.

Another feature of my invention is in the shield tube which surrounds the lamp to protect the same from injury. This tube is provided with a hemispherical or rounded end and a seat of corresponding shape is formed in the tubular sheath, so as to hold the same securely in place. This avoids the necessity of cementing or other similar mode of fastening which is for aseptic reasons undesirable.

In the drawings accompanying this specification I have illustrated one form of device embodying my invention.

The same reference number has been given to like parts in the several views.

Figure 1. is a side elevation of a device

embodying my invention. Fig. 2. is an enlarged view of one end of the device shown in Fig. 1. looking in the direction of the arrow 2. Fig. 3. is an enlarged view of the same end of the device shown in Fig. 1. from the opposite side, as indicated by the arrow 3. Fig. 4. is an enlarged sectional view of one end of the device, taken on the line x—x of Fig. 1. Fig. 5. is a view of one end of the device illustrating a modification in the form of the same.

At 1. is shown the main body portion of tubular sheath which is provided at one end with a cap, such as 2. A lamp 3, is positioned at one end of the device having one terminal, such as 4, connected to the cap and sheath and the other terminal connected through a sleeve 5 and collar 6 to a wire lead 7 which may be placed in a tube 8 which is in turn positioned in a slot in the wall of the tubular sheath 1. This is indicated by the "dot and dash" line extending lengthwise of the sheath in Fig. 1, and terminating in the connection indicated at 10. A suitable connection, as indicated at 11, may be provided for connecting the circuit to the sheath 1 in order to complete the lamp circuit. Suitable valves, as indicated at 12, may be provided if desired so that the device may be used for injecting liquids to the diseased portion of the body under treatment.

Fenestral openings, which are indicated at 13 and 14, are provided on opposite sides of the tubular sheath and near one end thereof. Between these openings on the interior of the sheath is located a transparent shield tube 9. This tube is provided with a rounded or hemispherical inner end and is open at the opposite end. The interior of the sheath is bored out and formed to correspond with the exterior surface of the shield tube and so forms a seat or socket in which the same is held securely and requires the use of very little or no cement to hold the same in place. As the cement and other similar materials which are used to secure the tube in place absorb the diseased and poisonous matter it becomes very essential to do away with the use of any such material as far as it is possible, and this is accomplished in a very simple manner by a construction such as described in my invention. The rounded inner end of this tube also possesses many advantages and is easily kept clean.

It will be seen that the shield tube 9 oc-

cupies only the forward portions of the fenes-
tral openings, leaving the rear portions of
these openings entirely unobstructed; and,
since these openings lead into the bore of the
instrument, it follows that the same open-
ings serve to permit the rays from the lamp
to illumine the portions of the body being
examined and also to furnish observation
apertures for the operator. Through, these
openings, too, pass such liquids as may be
admitted through valves 12.

The lamp 3 is provided with a metallic
sleeve 5 which fits closely in a collar 6 on the
interior of the shield tube 9. This supports
the lamp securely in place and the same is
protected against breakage and contact with
the body by means of the shield tube.

The fenestral openings 13 and 14 are so
positioned with relation to the lamp that the
light may emerge therefrom and allow the
inspection of objects in line with the axis of
the sheath. When the sheath is bent at one
end at an angle, as shown in Fig. 1., the light
from the opening 13 will illuminate objects
lying to the rear thereof and by using suitable
reflectors the same may be viewed with equal
facility. This arrangement of a single long
opening extending longitudinally on either
side of the lamp provides a very wide range
of vision both to the front and the rear. In
the angular construction shown in Fig. 1., the
opening on the concave side extends down
into the main portion of the sheath.

The modification shown in Fig. 5, illus-
trates a straight construction of sheath.

Various modifications may be made in the
details of construction herein shown and de-
scribed and many apparently widely differ-
ent embodiments of my invention may be
made without departing from the scope
thereof. It is intended therefore that the de-
scription and drawing herein be construed as
an illustration merely and not in a limiting
sense.

45 What I claim is:

1. A tubular surgical instrument adapted
to permit interior portions of the body to be
viewed through its bore and having an obser-
vation opening at its forward end leading
from said bore, and a lamp held in said end
and positioned to cast its rays through said
opening without barring the view of the
operator therethrough.

2. A tubular surgical instrument adapted
to permit interior portions of the body to be
viewed through its bore and having a lateral
observation opening at its forward end leading
from said bore and having its rear portion
unobstructed as to the view of the op-
erator, and illuminating appliances held in
said end and occupying the forward portion
of said opening to illuminate therethrough
the parts to be viewed.

3. A tubular surgical instrument adapted
65 to permit interior portions of the body to be

viewed through its bore and having an obser-
vation opening at its forward end leading
from said bore and having a portion un-
obstructed as to the view of the operator and
the passage of liquids from the interior of the
instrument, and illuminating appliances held
in said end and occupying another portion of
said opening to illuminate therethrough the
parts to be viewed.

4. In a surgical instrument adapted to
75 permit interior portions of the body to be
viewed and treated, the combination of a
tubular sheath having a lateral elongated
observation opening formed longitudinally
in its forward end, the rear portion of said
opening being entirely unobstructed, a trans-
parent shield tube fitting the bore of the
sheath at said end and occupying the forward
portion only of said opening, the rear end of
said tube being closed and the forward end
open, an electric lamp fitting into the forward
open end of said tube and facing rearward,
being positioned to shine through the forward
portion of the opening, electrical connections
for the lamp, and a removable rounded cap
90 mounted on the forward extremity of the
sheath and covering the forward ends of the
tube and lamp.

5. In a surgical instrument adapted to
enable interior portions of the body to be
viewed, the combination of a tubular sheath
95 having a lateral observation opening formed
in its forward end, a transparent shield tube
fitting the bore of said sheath at said forward
end and underlying said opening, the rear
end of said tube being closed and the forward
end open, an electric lamp fitting into the
forward open end of said tube and facing
rearward, being positioned to shine through
said opening, electrical connections for the
105 lamp, and a removable rounded cap mounted
on the forward extremity of the sheath and
covering the forward ends of the tube and
lamp.

6. In a surgical instrument adapted to
enable interior portions of the body to be
viewed, the combination of a tubular sheath
having a lateral opening formed in its for-
ward end, a transparent shield tube fitting
the bore of the sheath at said end and under-
lying said opening, the rear end of said tube
115 being closed and the forward end open, an
electric lamp fitting into the forward open
end of said tube and facing rearward, being
positioned to shine through said opening, a
removable rounded cap mounted on the for-
ward extremity of the sheath and covering
the forward ends of the tube and lamp, said
cap connecting with one of the terminals of
the lamp, and, with the sheath, being of con-
ducting material, and an insulated lead con-
nected with the other terminal of the lamp.

7. In a surgical instrument adapted to
enable interior portions of the body to be
viewed, the combination of a tubular sheath
130

having a lateral opening formed in its forward end, a glass shield tube fitting the bore of the sheath at said end and underlying said opening, the rear end of said tube being closed and the forward end open, said forward end of the tube being provided with an internal collar of conducting material, an electric lamp fitting into the forward open end of said tube and facing rearward, being positioned to shine through said opening and having an external conducting sleeve connected with one of its terminals and fitting inside said collar, an insulated lead passing along the sheath and connected with the 15 said collar, and a removable rounded cap mounted on the forward extremity of the sheath and covering the forward ends of the tube and lamp, said cap connecting with the

other terminal of the lamp, and, with the sheath, being of conducting material. 20

8. A tubular surgical instrument adapted to permit interior portions of the body to be viewed through its bore and having its forward end angled and provided with an observation opening in its rear side leading 25 from the bore of the instrument, and a lamp held in said angled end and positioned to cast its rays through said opening without barring the view of the operator therethrough.

Signed at the city of New York, in the county of New York and State of New York this 27th day of Aug., A. D. 1906.

REINHOLD H. WAPPLER.
